UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

WHEELED GUN CARRIAGE HAVING DIVERGIBLE TRAIL.

Application filed June 9, 1921. Serial No. 476,302.

To all whom it may concern:

Be it known that I, EUGÈNE SCHNEIDER, citizen of the Republic of France, residing at Paris, France, have invented new and useful Improvements in Wheeled Gun Carriages Having Divergible Trails, which invention is fully set forth in the following specifications.

This invention consists in improvements in guns of the known type, having divergible trails, wherein the trails carrying the anchoring devices are capable, for firing, of assuming oblique positions relatively to the combined wheeled axle and carriage head in which the gun pedestal (carrying the gun barrel) is adapted to swivel.

The improvements enable the pivotal axis of the gun pedestal to assume its vertical position at all times notwithstanding the transverse inclinations of the wheeled axle or the longitudinal inclinations of the carriage head.

For this purpose the swivel pivot pin of the gun pedestal, instead of being mounted directly in the carriage head, is mounted in a gun mount which is pivoted to the carriage head, and upon which the elevating mechanism of the gun barrel is supported.

The uprighting of the pivotal axis is produced either by a double transverse and longitudinal movement of the combined gun mount and elevating mechanism in the carriage head, or by a displacement of the gun mount relatively to the carriage head on the one hand, and of the combined carriage head and gun mount relatively to the wheeled axle on the other hand.

Various practical examples of this invention are illustrated in the accompanying drawings in which:

Figs. 1 to 6 inclusive illustrate a first practical example.

Fig. 1 is a longitudinal elevation of the general arrangement.

Fig. 2 is a corresponding plan.

Fig. 3 is a detail sectional elevation on the line 3—3 of Fig. 1.

Figs. 4 and 5 are sections on the lines 4—4 and 5—5 respectively of Fig. 3.

Fig. 6 is a section on the line 6—6 of Fig. 4.

Figs. 7 and 8 are respectively a longitudinal sectional elevation and cross-section on the line 8—8 of Fig. 7 of a second practical example of the invention;

Figs. 9 and 10 are respectively a longitudinal sectional elevation and a cross-section on the line 10—10 of Fig. 9 of a modification of the foregoing example;

Figs. 11, 12 and 13 are respectively the longitudinal sectional elevation, a half cross-section on the line 12—12 of Fig. 11 as regards the right-hand half and along XII—XII as regards the left-hand half, and a partial section on the line 13—13 of Fig. 12, of another modification of the constructional example shown in Figs. 7 and 8;

Figs. 14 and 15 are respectively a longitudinal sectional elevation and a cross-section on the line 15—15 of Fig. 14 of a modification of the foregoing example;

Figs. 16, 17 and 18 illustrate another constructional example respectively in longitudinal sectional elevation, transverse section on the line 17—17 of Fig. 16 and in horizontal section on the line 18—18 of Fig. 16.

Referring to Figs. 1 to 6, the improved gun comprises a wheeled axle, that is to say an axle A and two wheels B.

The carriage head C is fixed to the wheeled axle for firing. Nevertheless for transport, this carriage head may be suspended elastically from the wheeled axle by any suitable known means as is assumed in the illustrated example.

This suspension may comprise for instance, leaf springs D arranged between the axle A and the carriage head C, and which can be rendered inoperative by means of sprags E carried by screw-threaded rods that are actuated by means of hand wheels e.

When the sprags occupy the position shown in Fig. 3, the springs D are inoperative and the carriage head C thus bears directly upon the axle A.

The combination consisting of the two

trails F carrying the anchoring device at their rear ends, is capable of assuming the oblique position relatively to the combination constituted by the wheeled axle B—A 5—B and the carriage head C.

This possible obliquity of the trails relatively to the combined wheeled axle and carriage head may be produced by any suitable known means.

10 In the present case it is assumed that it has been effected by the means forming the subject matter of the French patent, Schneider & Cie., No. 530,656.

The trails F comprise a front element F¹ 15 enclosing an obtuse angle with the trail body and constructed in the form of a journal for which a bearing c is provided in the carriage head C.

A kinematic connection is established between the trail elements F¹. 20

According to the present invention, the pivot pin g of the gun pedestal G, (carrying the gun barrel) instead of having its footstep bearing formed in the carriage head 25 C, is situated in a gun mount H which is pivoted to the carriage head C.

The elevating mechanism bears upon this gun mount as hereinafter described. The pivot pin g may be returned into its normal vertical position by reason of the pivotal mounting of the mount H in the carriage head C, by means of two pins or two pairs of journals I and J formed on a hollow transverse member K through which the 30 axle A passes.

The transverse member K, whose middle portion of rectangular section straddles the wheeled axle so as to carry the latter along with it, terminates in two journals I that 40 are movable in corresponding bearings C¹ of the carriage head.

This same transverse member K has two journals J whose axis is at right angles to the axis of the journals I, and which are 45 movable in the bearings H¹ of the gun mount H.

It will be readily perceived that by rotating the gun mount H around the journals J it is possible to upright the pivot pin g 50 in the case of a transverse inclination of the wheeled axle A and the carriage head C, (carried by the said axle).

Similarly, by rotating the transverse member K in the bearings C¹, it is possible to 55 cause the combined transverse member and gun mount H to rotate in such a manner as to return the axis of the pivot pin g into a vertical plane in the case of a longitudinal inclination of the carriage head C.

60 The mechanisms that allow of effecting these uprighting movements may be constructed in practice in various ways.

In the example shown they are constructed as follows:—

65 In the carriage head C, a slide L is guided

by means of an extension L¹ and ribs L². The extension L¹ forms a nut for a screw M, journaled in the carriage head C and operable by means of a gearing m—m¹—m². On the hand wheel m² being actuated, the 70 slide L is caused to move in the plane of the longitudinal axis of the carriage head and to move along with it a transverse screw N which is journaled in the said slide.

On this screw there works a nut O which can be moved by actuating the hand wheel n that is fixed on an extension of the said screw. The nut O engages by means of a cylindrical stem o in a collar P furnished with two pivot pins p movable in a collar Q provided with two trunnions q, arranged at right angles to the pivot pins p and movable in bearings h projecting from underneath the gun mount H. 75 80 85

Assuming that the wheeled axle A is inclined transversely when the gun is moved into battery position or its inclination has become altered during the firing, and on the other hand that the carriage head C has assumed a varying inclination of the longitudinal direction, then by suitably actuating the hand wheels m² and n it will be possible to return the axis of the swivel pin g of the gun pedestal G always into the vertical position. 90 95 100

By actuating n, the gun mount H is carried round by the stem o and is caused to revolve around the axis of the journals J in such a manner as to correct the transverse inclination that can be assumed by the axis of the swivel pin g. 105

By actuating m², there are moved by means of the slide L, the nut L¹ and the gun mount H, and this latter moves the transverse member K which, by means of its journals I turns in the bearings C¹ of the carriage head, whilst the journal of the wheeled axle A turns in the wheels B.

The hereinbefore described apparatus is combined with a special construction of the 110 elevating mechanism, the latter being wholly supported by the movable gun mount.

The mechanism in the illustrated example comprises in the known manner toothed sectors R fixed to the gun carriage cradle S. 115 Motion is transmitted to these sectors (for elevating or depressing the cradle) by means of pinions T fixed on a shaft t which is journaled in a bracket U carrying a pivot pin u whose axis is situated in the prolongation 120 of the axis of the swivel pin g of the gun pedestal. A footstep bearing H² for this pivot pin u, is formed in the gun mount H. The bracket U forms in its turn a footstep bearing for a shaft V on which is fixed a 125 worm V¹ meshing with a worm wheel T¹ fixed on the shaft t. The shaft V is extended upwardly to work in a recess in the swivel pin g, and it carries a bevel pinion v which can be actuated by means of a gear. 130

ing $v^1-v^2-v^3$ carried by the gun pedestal.

Since the bracket U is to share in the movement of the gun pedestal G in the training movements of the gun, it is engaged by 5 means of a square collar U^1 upon a correspondingly shaped collar g^1 of the swivel pin g.

In the modification illustrated in Figs. 7 and 8, as in the preceding example, the 10 swivel pin g of the gun pedestal G is mounted in a gun mount H. This latter is pivoted directly by means of journals I in bearings C¹ of the carriage head in such a manner as to be able to assume, relatively to the latter, 15 a varying longitudinal inclination that will enable the axis of the swivel pin g to be returned into a vertical plane, irrespectively of the longitudinal inclination that is assumed by the carriage head C in firing.

20 On the other hand, the combined carriage head C and gun mount H are capable, in the case of a transverse inclination of the wheeled axle A, of being operated relatively to the latter for the purpose of returning the 25 axis of the swivel pin g into the vertical.

For this purpose the wheeled axle A is provided with two laterally projecting journals J engaged in bearings C² of the carriage head C.

30 The uprighting of the swivel pin g of the gun pedestal by the rotation of the journals I, is produced by actuating a hand wheel m², which actuates through a gearing m¹, m, a long screw M journalled in the carriage head C. The rotation of this screw causes the movement of a nut L which is engaged by means of pins L² in bearings formed underneath the gun mount H.

35 The operating of the combined carriage head C and gun mount H around the journals J, is produced by the actuation of a worm W whose spindle W¹, provided with an actuating hand wheel W², is journalled in the carriage head C. The screw W meshes with a helically toothed sector X fixed on one of the journals J.

40 The movement of the screw W on the fixed sector X causes the carriage head C to turn in such a manner that the gun mount H and the gun pedestal G carried by it shall be caused to share in this movement.

45 The elevating mechanism comprises, as in the preceding example, toothed sectors R fixed to the gun carriage cradle S, and to which motion is transmitted through pinions T fixed on a shaft t. This shaft is journalled in a bracket U carrying a pivot pin u whose axis is situated in the prolongation of the axis of the swivel pin g of the gun pedestal. A gearing $v^3-v^2-v^1-v$ transmits the motion through a shaft V mounted in an axial recess of the swivel pin a and carrying a worm v¹ by which the motion is transmitted to a helical wheel T¹ fixed on the shaft t.

This elevating mechanism bears, as will be seen, upon the gun mount H, and moves with the latter in the uprighting movements in the case of a longitudinal or transverse inclination in firing.

70 In the modification illustrated in Figs. 9 and 10 the journals I are formed on the gun mount H at the lower part of the latter, and the upper part of the gun mount, in this rocking movement around the axis of the 75 journals, is guided on the carriage head by slides H³ working on arc-shaped ribs having their centre on the pivotal axis.

In the modification illustrated in Figs. 11, 80 12 and 13, the pivot for the transverse up-righting of the combined carriage head C and the gun mount H carrying the gun pedestal G, is constituted by a removable axle J which extends through the wheeled axle A and two frame plates of the carriage head C.

85 The removability of the rocking axle J allows of providing an elastic suspension for the road wheels between the carriage head C and the axle A. This suspension may, for instance, comprise leaf springs D whose buckle D¹ may be suspended by means of links d¹ and blocks a fixed to the axle A, whilst the main leaf is pivoted by shackles to the carriage head C.

90 For firing, the links d¹ are unhooked and 95 the axle J is placed in position.

The pivotal motion of the combined carriage head, gun mount H and gun pedestal G around the axle J may be produced, as shown in Fig. 11, by moving the carriage head C by means of a nut y formed on the actuating hand wheel Y and worked on a screw-threaded rod Y¹ jointed at y¹ to the wheeled axle.

100 For transport, if it be desired to bring the elastic suspension into operation, the combined nut y and screw Y¹ is turned down into the position indicated in dot and dash lines (Fig. 12), thus disengaging the nut y from the notch c¹ formed in the carriage head wherein the said nut was held by its end collars.

105 In the modification illustrated in Figs. 14 and 15, the elastic suspension between the carriage head C and the wheeled axle A is 110 constituted by a leaf spring D arranged in the longitudinal axial plane of the wheeled axle. The buckle D¹ of this spring is here fixed to two frame plates D² pivoted on pins C³ projecting internally from the bearings 115 of the pin J.

120 For transport, in this case it is sufficient to withdraw the pin J and to turn down the actuating hand wheel Y, whereas to render the suspension inoperative it is sufficient to 125 reinsert the pin J.

125 In the constructional form illustrated in Figs. 16, 17 and 18, the gun mount H in which the swivel pin g of the gun pedestal G is mounted, has two laterally projecting 130

trunnions I, by means of which it is journaled in the carriage head C for the purpose of being uprighted in the longitudinal direction.

5. With a view of enabling the transverse uprighting of the combined carriage head C and gun mount H, the wheeled axle is divided into two sections each of which A¹ is pivoted by an arm A² around a prolongation of the corresponding axle or trunnion I. Each section of the wheeled axle B—A¹—A² is guided by means of a slide block A⁴ in an arc-shaped slotted guide C⁴ of the carriage head, centered on the axis of 15 the trunnions I.

The pivotal movement of the gun mount H for the purpose of longitudinal uprighting, is produced by a means which is identical to that indicated in the example illustrated in Figs. 7 and 8.

20. The uprighting mechanism is not shown, neither is the elevating mechanism. As regards the uprighting movement in the transverse direction of the combined carriage head C and gun mount H, it is produced by 25 actuating in the direction corresponding to that of the inclination, screw-jacks pivoted between the carriage head and the wheeled axle section. These screw-jacks comprise for 30 each wheeled axle section a screw-threaded rod Z which is pivoted at its upper end to the corresponding section of the axle A and works in a nut Z¹ that is capable of turning in the carriage head C.

35. Rotational motion can be imparted to the nuts Z¹ so as to cause them to turn in opposite directions to each other. For this purpose bevel teeth are formed on these nuts, meshing with bevel pinions Z² fixed on the 40 ends of the shaft Z³.

Motion is imparted to the shaft Z³ by 45 means of a pinion Z⁴ which meshes with one of the pinions Z² and which is fixed on a shaft Z⁵ operable by means of a hand wheel Z⁶ and journaled in the carriage head C.

50. For transport an elastic suspension may be provided between the axle sections A¹ and the carriage head C, by means of a leaf spring D whose buckle D¹ is formed in the carriage head; the main leaf of the spring being hung by means of shackles D² from the axle sections A¹. When it is desired to render the elastic suspension operative, it is 55 of course necessary to undo the coupling between the screws Z and the wheeled axle sections.

I claim:

1. In a wheeled gun mounting provided with an axle, a carriage mounted on said axle and movable relative thereto, a gun mount pivotally supported by said carriage, a gun pedestal supported by said gun mount, gun elevating means carried by said gun mount means to turn said mount in a 60 plane at right angles to said axle, together 65

with means for turning the mount in a plane parallel to said axle.

2. In a wheeled gun mounting provided with an axle, a carriage mounted on said axle and movable relative thereto a pair of 70 divergible trails pivotally secured to said carriage, a gun mount pivotally supported by said carriage, a gun pedestal supported by said gun mount, means to turn said mount in a plane at right angles to said axle, means for turning the mount in a plane parallel to said axle, and gun elevating means carried by said mount.

3. In a wheeled gun mounting provided with an axle, a carriage mounted on said 80 axle and movable relative thereto a pair of divergible trails pivotally secured to said carriage below the horizontal plane of said axle, a gun mount pivotally supported by said carriage, a gun pedestal supported by 85 said gun mount, means to turn said mount in a plane at right angles to said axle, means for turning the mount in a plane parallel to said axle, and an elevating mechanism 90 carried by said mount and adapted to turn therewith.

4. In a wheeled gun mounting provided with an axle, a carriage mounted on said axle and movable relative thereto gun-elevating means carried by said gun mount, an elastic suspension between the carriage and said axle, a gun mount pivotally supported by 95 said carriage, a gun pedestal supported by said gun mount, and means to turn said mount in a plane at right angles to said axle.

5. In a wheeled gun mounting provided with an axle, a carriage mounted on said axle and movable relative thereto, an elastic suspension between the carriage and said axle, a gun mount pivotally supported by said carriage, a gun pedestal supported by 105 said gun mount, gun-elevating means carried by said gun mount, means to turn said mount in a plane at right angles to said axle, together with means for turning the mount in a plane parallel to said axle.

6. In a wheeled gun mounting provided with an axle, a carriage mounted on said axle and movable relative thereto, an elastic suspension between the carriage and said axle, means for rendering said suspension inoperative, a gun mount pivotally supported by said carriage, a gun pedestal supported by 110 said gun mount, gun-elevating means carried by said gun mount, and means to turn said mount in a plane at right angles to said axle.

7. In a wheeled gun mounting provided with an axle, a carriage movably mounted thereon, divergible trails pivotally secured to said carriage, a gun mount pivotally supported by said carriage, a gun pedestal supported by 125 said gun mount, an elevating mechanism supported by said gun mount, and 130

means for moving said mount to a vertical position from any inclined position.

8. In a wheeled gun mounting provided with an axle, a carriage supported thereon, a gun mount pivoted in said carriage, a gun pedestal supported by said gun mount, a gun cradle supported by said pedestal, an elevating mechanism comprising toothed sectors fixed to said cradle, a bracket carried by said mount, a shaft carried by said bracket, pinions mounted on said shaft and adapted to mesh with said sectors, a worm-wheel mounted on the shaft, a shaft movably mounted in said pedestal, a worm carried by said last-named shaft and adapted to mesh with said worm wheel, and means for moving said last-named shaft.

9. In a wheeled gun mounting provided with an axle, a carriage mounted on said axle for rotation about the longitudinal axis of the same, a gun mount pivotally supported by said carriage to turn on an axis at right angles to said axle, and a gun pedestal supported by said gun mount.

10. In a wheeled gun mounting provided with an axle, a gun pedestal mounted to turn in a plane parallel to said axle, a carriage supporting said pedestal and mounted to turn around the axle in a plane transverse thereto, and means for imparting said turning movements to said carriage and pedestal.

11. A wheeled gun mounting comprising

an axle, a carriage mounted on said axle, a hollow member through which said axle passes, a gun mount movably supported by said hollow member, means for rotating said mount transversely of said carriage, and means for rotating said mount longitudinally of said carriage.

12. A wheeled gun mounting comprising an axle, a carriage mounted on said axle, divergible trails movably secured to said carriage, a hollow member through which said axle passes, a gun mount movably supported by said hollow member, means for rotating said mount transversely of said carriage, and means for rotating said mount longitudinally of said carriage.

13. A wheeled gun mounting comprising an axle, a carriage mounted on said axle, an elastic suspension between said axle and the carriage, means to render said suspension inoperative, a hollow member through which said axle passes, a gun mount movably supported by said hollow member, means for rotating said mount transversely of said carriage, and means for rotating said mount longitudinally of said carriage.

In testimony whereof I have signed this 60 specification.

EUGÈNE SCHNEIDER.
